US00D756974S

(12) **United States Design Patent**
Glezerman et al.

(10) **Patent No.:** **US D756,974 S**
(b4) **Date of Patent:** **** May 24, 2016**

(54) **COMMUNICATION DEVICE**

(71) Applicant: **CARDO SYSTEMS, INC.**, Pittsburgh, PA (US)

(72) Inventors: **Abraham Glezerman**, Tel Aviv (IL); **Abraham Moato**, Rishon LeZion (IL); **Uri Gilboa**, Givatayim (IL)

(73) Assignee: **CARDO SYSTEMS, INC.**, Pittsburgh, PA (US)

(**) Term: **14 Years**

(21) Appl. No.: **29/515,270**

(22) Filed: **Jan. 21, 2015**

(30) **Foreign Application Priority Data**

Aug. 7, 2014 (IL) 55893

(51) **LOC (10) Cl.** **14-03**

(52) **U.S. Cl.**

USPC **D14/230**; D14/206

(58) **Field of Classification Search**

USPC D14/230, 238.1, 238, 496, 507, 509, D14/137, 155, 188, 248, 142, 205, 206, 223, D14/192, 225, 226, 432, 433; 2/421, 422; 181/129, 130, 135; 379/430, 431; 381/380, 381; 455/90.3, 575.2, 575.7; 343/702, 703, 878

CPC H04R 25/00; H01Q 1/12; H01Q 1/24

(57) **CLAIM**

The ornamental design for a communication device, as shown and described.

DESCRIPTION

FIG. 1 is a perspective view of a communication device;

FIG. 2 is a bottom view thereof;

FIG. 3 is a top view thereof;

FIG. 4 is a right side view thereof;

FIG. 5 is a left side view thereof;

FIG. 6 is a front view thereof; and,

FIG. 7 is a rear view thereof.

1 Claim, 2 Drawing Sheets
